UNITED STATES PATENT OFFICE.

CELORA MARTIN STODDARD, OF PHOENIX, ARIZONA.

ROUTE-INDICATOR FOR AUTOMOBILES.

1,200,262.

Specification of Letters Patent.

Patented Oct. 3, 1916.

Application filed February 16, 1914. Serial No. 818,937.

To all whom it may concern:

Be it known that I, CELORA M. STODDARD, a citizen of the United States, and a resident of Phoenix, in the county of Maricopa and State of Arizona, have invented an Improvement in Route-Indicators for Automobiles, of which the following is a specification.

My present invention relates to means whereby the driver of an automobile may have the benefit of a complete log of a particular route, the readings of which will be changed as the route is traversed to show the road and certain directions in connection therewith for some distance in advance, say a distance of approximately 50 yards.

The object of my invention is to provide such a device in the nature of a movable indicator, the movement of which may be derived from the usual odometer to constantly change its position as the route is traversed and uniformly position the readings properly in the sight of the driver.

In view of these facts I have termed the present invention a route indicator, taking into consideration its structure and its several functions, both of which will be clearly apparent from the following description in which reference is made to the accompanying drawings, forming a part of this specification, and in which,

Figure 1 is a plan view illustrating the practical application of my invention, those portions of the motor vehicle to which my invention is adjusted, being illustrated in dotted lines. Fig. 2 is a face view of my invention. Fig. 3 is a side elevational view of the same. Fig. 4 is a vertical longitudinal section. Fig. 5 is a front elevation, partly broken away and in section with the cover open. Fig. 6 is a detail perspective view of the take up roller, and Fig. 7 is a plan of the indicating web.

Referring now to these figures it will be seen that the several parts constituting my invention are housed within a substantially rectangular box A which may be suitably supported upon a portion of a motor vehicle and the like, preferably upon the dash thereof as shown in Fig. 1, by means of a bracket B secured to the rear of the box A and adapted to be fastened to the dash or other parts by means of screws and like fastenings.

At the front of the box is a cover C which is hinged thereto at its lower edge as indi-

cated at c and which is provided with a transparent section C' through which the interior of the box may be viewed, a spring or other catch c' secured to the upper end of the box being utilized to engage the upper end of this cover in order to normally maintain the same in closed position.

Referring now particularly to Figs. 4 and 5 it will be seen that the box A is provided with a pair of guide rods a and a' located transversely thereacross and respectively adjacent the upper and lower edges of the transparent cover section C' when the cover is closed, the functions of these guide rods being to receive the web, to be herein-after described, and thus hold the web in full view of the driver through the said transparent section.

In the rear of the guide rod a, the box A is provided at one side with an opening and at its opposite side with a bearing a² transversely alined with the said opening, said bearing receiving the reduced inner end d of a web holding roller D adapted to be extended through the opening just mentioned. As will be seen particularly in Fig. 5, that portion of the shaft of roller D which, in the operative position of the roller, extends within the box A, is squared, to receive a similarly shaped spool e at the inner end of the web E, the shaft of roller D also having a milled knob D' at its outer end and a circumferential recess adjacent to said outer end with which a pivoted latch member d' mounted upon the adjacent outer surface of the box A, is adapted to engage in order to normally hold the roller against longitudinal displacement. It will also be seen that box A is provided in the rear of the rods a', with an aperture at one side and an inwardly projecting socket a³ alined with this aperture and also apertured for the reception of a take up roller F, this roller having its shank, which is provided with an intermediate hook f, thus extended through both of the box sides and provided at one end with an enlarged head F' provided with a squared socket f' and movable, by longitudinal movement of the said roller, within and out of the box sides socket a³ to respectively disengage from and engage with the squared end g of the projecting shaft of the odometer G along side of which my invention is intended to be located as particularly shown in Fig. 1. At its opposite end the take up roller F is provided with a project-

ing handle f^2 and adjacent to this handle is a circumferential groove f^3 with which a latch piece f^4 , similar to the latch piece d' is adapted to engage to normally prevent the 5 roller from longitudinal displacement.

The web E which is normally wound upon its squared spool e , is disposed within the box and the roller D is initially passed through the spool e and moved into operative position as shown, the outer end of the 10 web being passed outwardly and over the guide rods a and a' and having an intermediate eye e' by which it may be engaged with the hook f of the take up roller F on to 15 which it is to be rolled when the latter is in engagement with the rod g of odometer G when the vehicle is in movement.

The web E is provided along one longitudinal edge with a series of numerals indicating the miles traversed along the particular route and has a reversed series of numerals along its opposite edge indicating the number of miles to be traversed to reach the end of the route, these series of numerals 20 being respectively indicated at e^2 and e^3 in Fig. 7. The web is also to be provided with readings of various land marks, buildings and like points to which the attention of the driver can be intelligently drawn and also 25 with a series of characters which are indicated at e^4 in Fig. 7 in the nature of directions of which the driver should take particular notice, " o " indicating street car crossings, " x " indicating danger, two parallel vertical lines with a crossing transverse line indicating railroad crossings, an inclined and curved line indicating either an up or down grade depending upon the direction of its inclination, and a vertical line 30 with a horizontal line added at one end thereof indicating a turn either to the right or the left depending upon the direction in which the horizontal line is extended from the vertical line. These various direction 35 marks are shown on the web in Fig. 7 although it is to be understood that in practice a great many other such marks will be necessary in order that the readings may properly conform to the route.

50 It is also to be understood that the several readings will be required in practice to be properly spaced to conform to the landmarks on the route and also to the working of the parts of the route indicator but inasmuch as this spacing will depend to a great extent upon the particular route, I have not attempted to show any particular spacing at present in the drawings.

When the end of the route has been 60 reached or the vehicle turned on to a new route and it is desired to substitute a different web, the latch piece f^4 of the take up roller F is lifted and this roller moved slightly to the right in a longitudinal direction according to Fig. 5 in order to dis-

engage its end from the shaft of the odometer. The holding roller D may then be rotated by grasping its milled knob D' to rewind the web thereon after which its latch piece d' is raised and roller D may then be withdrawn and the web lifted out of the box A preparatory to the insertion of another web.

The box A may be provided with an indicating pointer A' extending inwardly 75 from one side thereof and forwardly of a plane connecting the guide rods a and a' in order that the web may be properly positioned in the first instance before the cover C is closed, this cover also having an indicating pointer C^2 which registers with pointer A' when the cover is closed.

Thus by the use of my invention the readings for a particular route are at all times within convenient sight of the driver 85 of a vehicle without necessitating adjustment after starting and do away with the necessity for frequent reference to road maps and the perusal of the present style log books which require the withdrawal of 90 at least one hand from the control of the vehicle.

It is to be understood of course that it is not essential that my invention be used in connection with an odometer as I have 95 shown, inasmuch as the usual flexible shaft G' of such devices may be applied directly to the take up roller F provided it is geared in any well known manner so that the parts are turned in the proper relation to 100 the speed of the vehicle.

I also propose to provide the web with log readings upon its reverse surface and thus provide for guidance along a certain route both coming and going, it being apparent from the description of the structure of the parts before described that the web may be readily reversed on its shaft and may be passed from the guide rods in the manner indicated in dotted lines at E' in 110 Fig. 4.

I claim:

1. In a route indicator of the character described, the combination of a casing having a transparent section, a web movable 115 within the casing, a pair of reels mounted through the casing and upon which the web is carried, each of said reels being longitudinally movable with respect to the casing and having an annular groove adjacent one 120 side of the casing, means carried by the casing and normally engaging said groove to prevent displacement of the reels, one of said reels having a handle at one side of the casing, and a squared end socket at the 125 opposite side of the casing, all for the purpose described.

2. In a route indicator, the combination of a web having route log readings, a holding roller with which said web is detach- 130

ably connected, a take up roller with which the web is detachably engaged, means for driving the said take up roller in relation to the speed of the vehicle on which the route 5 indicator is used, and a box through which said rollers are journaled for longitudinal movement, the holding roller being wholly removable from the box and the take up roller having a limited longitudinal move-

ment with respect to the box whereby to engage with and disengage from the said driving means, each of said rollers having an annular groove, and latches carried by the box for engagement in the said groove.
